REAR VIEW MIRROR

Handry J. Malachowski, Jersey City, N. J., assignor to
Yankee Metal Products Corp., Norwalk, Conn., a corporation of New York

Application August 6, 1954, Serial No. 31,760

Term of patent 14 years

(Cl. D14—6)

Fig. 1 is a front view of a rear view mirror, showing my new design;

Fig. 2 is a rear view thereof;

Fig. 3 is a side elevation thereof; and

Fig. 4 is a perspective view thereof, as seen from the rear.

The dominant features of my design reside in the portion shown in full lines.

I claim:

The ornamental design for a rear view mirror, substantially as shown and described.
